UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

MULTIPLE CASTING MACHINE

Application filed August 19, 1926. Serial No. 130,208.

- This invention relates to a machine for casting metal, particularly for making stereotype printing plates in a plurality of molds or casting boxes.
- 5 The principal objects of this invention are to provide a single pump with a single spout so arranged as to deliver to each of the molds at different times; to provide the spout and certain pump connections in such relationship to each other that the pump itself will indicate to which mold it is to deliver, and to provide means whereby it cannot deliver to any other mold or to more than one mold at a time. The invention also involves a simplification of devices designed for supplying a plurality of molds with metal. This invention therefore relates mainly to the pump and its relationship to the molds or casting boxes.
- 10 Further objects and advantages of the invention will appear hereinafter.
- Reference is to be had to the accompanying drawings in which
- Fig. 1 is a plan of a machine constructed in accordance with this invention;
- 15 Fig. 2 is a central sectional view of the pump taken on the line 2—2 of Fig. 1;
- Figs. 3 and 4 are horizontal sectional views on enlarged scale of the pump on the line 20 3—4 showing the valve and handle in two different positions; and
- Fig. 5 is a side elevation of the valve plate.
- I have shown the invention as applied to a combined casting and finishing plant in which two casting boxes 10 are located with their axial lines intersecting at the center of a vertical shaft 11 on which a finishing machine 9 is pivoted. The details of this finishing machine do not constitute a part 25 of this invention as they are fully shown in my co-pending application, Serial No. 121,403, filed July 9, 1923, and they do not constitute a part of the present invention.
- It is sufficient to say that the finishing machine can swing from full line to dotted line position, supported by rollers 13 on an arcuate track 14. Operating handles 15 are shown.
- The two casting boxes shown are located at an angle to each other, although that is not essential to this invention. The casting
- boxes are shown in Fig. 1 in vertical position and two spouts 20 are shown adapted to deliver metal into the two casting boxes one at a time. These spouts, as shown in Fig. 2, are fixed to a platform 21 mounted on the top of the melting pot 22 or furnace and in stationary position. They also have pipes 23 extending down inside the melting pot and terminating in the top of the cylinder 24 thereof. These two spouts have openings at a distance apart in the top of the cylinder and are adapted to be filled by the passage of metal upwardly from the cylinder.
- The pump is shown of an ordinary simple type except with certain modifications as will appear. It comprises a column 25 preferably cast integral with the platform 21 and cylinder 24. In this column is a rotatable hollow shaft 26 adapted to swing back and forth, limited by stops 27.
- The shaft is provided with a bracket 28 extending outwardly on which is pivoted a pump operating handle 29. This handle 29 operates the piston rod 30 in the usual way, this rod extending down through the hollow shaft into the cylinder. The cylinder has ports 32 through which the metal flows into it and the raising of the piston 31 will force the metal up into the cylinder and into one of the pipes 23 and spouts 20.
- Inside the cylinder and at the top thereof is located a valve plate 33 fixed to the hollow shaft 26 so as to turn with it. The plate is provided with a port 34, located normally, directed under the handle 29 so that it will swing with the handle about the axis of the shaft 26 to two different positions. In one of these positions it will register with one of the pipes 23 and cause the metal to be delivered to one of the casting boxes 10. In the other position it will register with the other one and deliver to the other box. Therefore it is obvious that the operator turns the handle 29 to either the full or dotted line position in Fig. 1 and then, when he pulls down on it, the metal will be delivered to that one of the molds toward which the handle points. This constitutes a very simple and convenient device for delivering to more than one mold, and it is not possible for the op-

erator to have any uncertainty in his mind as to what mold the pump will deliver to.

When he pulls down on the operating handle the molten metal which has filled the interior of the cylinder through the ports 32 will be forced into the port 34 and into the desired spout 23 and into that box. One of the pipes 23 is always closed so that the pump cannot deliver to both molds at the same time, even a small quantity of metal. The entire charge is delivered into the selected mold.

The valve plate 33 is kept in close contact with the roof of the cylinder owing to the fact that the iron of which it is made normally floats in stereotype metal and to the fact that the molten metal being pumped upwardly will naturally tend to force this plate into close contact with the lower surface of the cylinder head. This insures the exclusion of metal from the spout which happens to be closed by the valve.

Although I have illustrated and described only one form of the invention I am aware of the fact that other modifications can be made therein by any person skilled in the art without departing from the scope of the invention as expressed in the claims. Therefore, I do not wish to be limited to all the details of construction herein shown and described, but what I do claim is:—

1. In a stereotype plate casting machine, the combination with a plurality of casting boxes, of a single means for filling the boxes with molten metal, a pouring spout terminating just over each casting box and means whereby the filling means can be operated to deliver to any spout and at the same time close the others.

2. In a stereotype plate casting machine, the combination with a plurality of casting boxes, of a single means for filling the boxes with molten metal, and a pouring spout terminating just over each casting box, said spouts being mounted in stationary position.

3. In a stereotype plate casting machine, the combination with a plurality of casting boxes, of a single pump, a separate pouring spout terminating just over each box extending thereto from the pump, pipes in the pump, each communicating with one spout, and a valve plate capable of establishing connection between the pump and any one pipe and closing the others.

4. In a casting machine, the combination with a plurality of molds, of a pump adapted to deliver metal to any of said molds, the molds being arranged at equal distances from the center of the pump, said pump having a piston and rod, an operating handle mounted to turn on the axis of the rod, and a valve mounted to turn with the handle and having a port arranged to connect the pump with one mold at a time according to the position of the handle.

5. In a casting machine, the combination with a plurality of molds, of a pump adapted to deliver metal to any of said molds, the molds being arranged at equal distances from the center of the pump, said pump having an operating handle mounted to turn, and a valve mounted to turn with the handle and having a port arranged to connect the pump with a mold when the pump handle is in a position pointing toward that mold.

In testimony whereof I have hereunto affixed my signature.

HENRY A. WISE WOOD.
